UNITED STATES PATENT OFFICE

LOUIS A. ANDERSON, OF ATTLEBORO, MASSACHUSETTS, ASSIGNOR TO R. & G. COMPANY,
OF ATTLEBORO, MASSACHUSETTS

VANITY CASE

Application filed May 8, 1929. Serial No. 361,323.

This invention relates to certain new and useful improvements in vanity cases and the primary object thereof is to provide a case having an improved loose powder holding and dispensing compartment, and also an improved rouge containing compartment and more particularly to thereby provide a case of more compact and also simplified construction, enabling the parts to be easily and 10 quickly assembled.

Further, the invention aims to improve the manner of connecting the finger engaging or carrying bail and also the mirror hinging means and to provide improved latching 15 means for the mirror.

The invention has still further and other objects which will be later set forth and be manifested in the course of the following description.

20 In the drawings:

Figure 1 is a side elevation of the invention, the parts being in closed position;

Figure 2 is a top plan view, the parts being shown in open position.

25 Figure 3 is a side edge elevation of Figure 1,

Figure 4 is a section on line 4—4 of Figure 2, and

Figure 5 is a bottom plan view similar to 30 Figure 2 showing however, the mirror closed and the bail engaging ears in different stages in manufacture.

In proceeding in accordance with the present invention, a case is provided having a 35 body 1 and a cover 2 each being of concavo-convex form as shown in Figure 4. The body and cover are shown as of hexagonal outline, although any desired shape may be employed, and are hingedly connected.

40 The body 1 has a top plate 4, while the cover 2 has a corresponding top plate 5, the adjacent sides of the plates being extended and rolled to form hinge knuckles 6 for receiving the usual pintle 7. As shown in Figure 45 the top plate 4 has ears 8 extended therefrom which are rolled to form eyes rotatably receiving the inturned ends 9 of a finger engaging or carrying bail 10 therein.

For the purpose of forming a loose powder 50 compartment, in the body 1 the top plate 4

thereof is formed with a circular opening surrounded or defined by a circular flange 11 which extends toward the concave bottom, and which has its lower edge inturned to form a ledge 12. A spring latching ring 13 55 loosely surrounds the flange 11 in eccentric relation thereto, and has a T-shaped projection 14 which is received in a seat 15 provided therefor in the flange 11. A finger piece 16 is provided on the ring 13 opposite to the 60 T-projection 14 and has a latch 17 thereon, which extends through an opening provided therefor in the plate 4 and is adapted to snap into a keeper 19, formed on the plate 5. By 65 pressing on the finger piece the ring 13 is compressed and the latch thus released from the keeper 19. A bottom disk 20 seats on and is soldered at 21 to the ledge 12 and has an opening 22 to enable the powder compartment to be filled and to also dispense the 70 powder through the perforations 23 in an upper control disk 24. The disk 24 is rotatably connected to disk 20 by a rivet 25 and has an opening 26 which when in register with opening 22 enables the powder 75 compartment to be refilled. A finger projection 27 extends outwardly from disk 24 to enable same to be rotated.

A mirror 28 is hinged to the plate 5 by means of a pin 29 the latter being headed 80 into engagement with a pair of spaced ears 30 that are struck out at the ends of an opening 31, the opening receiving an extension 32 formed on the mirror frame and which is rolled to form an eye that embraces the pin 85 and is received between the ears 30.

The plate 5 is formed with a right angular circular inwardly extending and integral wall 33, the latter having a lateral portion 34 which is disposed parallel to the plate 90 and forms a seat for the mirror frame. A lip 35 extends inwardly from the seat 34 and is engaged by the flange 36 of a cup 37 which is soldered to the lip. The cup 95 removably receives a rouge cake 38 therein.

For the purpose of latching the mirror in position, a catch 39 is formed on the mirror frame, the latter being provided also with a finger nail recess 40 in its periphery, the catch being formed to snap into engagement 100

with a keeper 41 formed on the wall 33 adjacent to a finger nail curved depression 42, the latter affording ready access to the nail recess 40 in the mirror frame.

5 From the foregoing it will be seen that a very compact structure is afforded and that a minimum of soldering is involved, in which regard, the tops 4 and 5 are also soldered to the body 1 and cover 2, at their edges.

10 Having thus described my invention what I claim as new and desire to secure by Letters Patent is:—

15 1. In a vanity case, a member having a mirror seat, and having spaced struck-out ears which extend upwardly from said member and which form an opening, a pin headed at its ends into engagement with the ears, and a mirror frame receivable on said seat and formed with an extension which is received in said opening and which is rolled about said pin in the space between the ears.

20 2. In a vanity case, a body having a flange formed with a seat, a spring latching ring having a T-shaped projection received in said seat and having a finger piece opposite to the projection and carrying a catch, and a cover hinged to the body and having a keeper to receive the catch.

25 3. In a vanity case, a body having a bottom and a top formed with a circular flange which extends toward the bottom, a hinged cover for the body having a keeper, a spring ring eccentric to the body and surrounding said flange and secured thereto, at a point adjacent to the hinge, a finger piece on the ring opposite to said point of securing thereof, a catch on the ring extending through the top and engageable with the keeper of the cover.

30 4. In a vanity case, a body having a top and a hinged cover, a spring latching ring secured to the body adjacent to said hinge of the cover and having a finger piece and a latch which latter projects through the top, and a keeper on the cover to engage the latch.

35 5. In a vanity case, a body having a ring like top plate provided with an inwardly extending circular flange, the inner edge of which is turned toward the center of the plate to form a ledge disposed substantially parallel to the bottom of the body, a pair of disks pivoted at their centers and being both disposed within the flange, the innermost disk being seated upon the ledge and secured thereto, the innermost disk having an opening and the outermost disk having a group of perforations and a filling opening, which latter and the group of perforations are selectively movable to register with the opening of the innermost disk.

40 6. In a vanity case, a member having a bottom and a top the latter formed with an inward extending circular wall and with a portion parallel to the top to provide a mirror seat, said seat having a marginal lip at

its edge which extends toward the bottom and which is spaced from the latter, a rouge cup having a bottom and having a flange which telescopes the lip and which is held in position thereby, and a hinged mirror receivable in the seat.

7. In a vanity case, a body having a top plate which latter is provided with a pair of spaced integral extensions, rolled to form hinged knuckles, and a bail having ends rotatably received in said knuckles.

75 In testimony whereof I have signed my name to this specification.

LOUIS A. ANDERSON.
